UNITED STATES PATENT OFFICE

MORRIS POLEY, OF LARCHMONT, NEW YORK, ASSIGNOR TO BEAR MILL MANUFACTURING COMPANY, INC., OF NEW YORK, N. Y., A CORPORATION OF NEW YORK

DESIGN FOR A TEXTILE FABRIC

Application filed May 24, 1933. Serial No. 48,199. Term of patent 3½ years.

To all whom it may concern:

Be it known that I, MORRIS POLEY, a citizen of the United States, residing at Larchmont, in the county of Westchester and State of New York, have invented a new, original, and ornamental Design for Textile Fabrics, of which the following is a specification, reference being had to the accompanying drawing forming a part thereof.

In the drawing:

The figure is a plan view of a textile fabric showing my new design. A single unit of my design is substantially comprised within the area defined by the indicating lines shown on the drawing.

I claim:

The ornamental design for a textile fabric as shown and described.

In testimony whereof, I hereto affix my signature.

MORRIS POLEY.
